JOHN NELSON, OF NEWTON, IOWA, ASSIGNOR TO AUTOMATIC WASHER COMPANY, OF NEWTON, IOWA, A CORPORATION OF DELAWARE

DRIVING MECHANISM FOR WASHING MACHINES

Application filed February 6, 1926. Serial No. 86,382.

This invention relates to driving mechanism for washing machines.

One of the objects of the invention is to provide driving mechanism for washing machines permitting the movement of the dolly without the positioning of the driving means therefor upon the upper side of the lid.

Another object is in the provision of driving means for a dolly type of washing machine, said driving means and clutching mechanism therefor being mounted entirely beneath the lid and top of the washer.

Still another object is the provision of a dolly type of washing machine, wherein the driving mechanism therefor is of the rack and gear type, said mechanism being fashioned in a manner to permit mounting thereof beneath the top of the washer, and still permitting optional raising and lowering of the lid to facilitate entry and removal of materials to be washed.

A further object lies in the provision of a particularly fashioned spring tensioned rack, the same being mounted upon the under side of the washing machine cover and being adapted to engage the driving gears for the dolly, the same being attached to a lid member capable of being raised or lowered as desired.

A still further object is to provide driving means for a dolly type of washing machine, said driving means including a spring tensioned rack member fashioned for relative engagement with gear mechanism for the dolly, the same being positioned upon the pivoted lid portion.

Other objects will appear in the following specification taken in connection with the annexed drawings, in which—

Fig. 1 is a front elevation, partially in section, showing in general the mounting of the driving mechanism herein in connection with the dolly;

Fig. 2 is a plan view, from above, portions thereof being shown in section, of the driving mechanism for the dolly;

Fig. 3 is a sectional view taken on the line 2—2 of Fig. 2;

Fig. 4 is a sectional view taken on the line 4—4 of Fig. 2;

Fig. 5 is an enlarged detail of the mechanism for accomplishing the release of the rack from the gear drive for the dolly.

Referring to the drawings, there is shown in Fig. 1 a general view of the driving mechanism in connection with the dolly, wherein it may be observed that the cover and lid portion of the washing machine tub carries none of the driving elements which are so common to the conventional type of washer.

Referring more particularly to the mechanism, there is shown at 10 the well known tub portion. This tub 10 is suitably attached to a steel base 11, to which is secured a supporting frame 12, carrying the power means, namely, the electric motor 13. The four legs 14 support the tub and frame in the conventional manner. The supporting frame 12 similarly provides the means for locating in a fixed manner thereon a gear casing 15, said gear casing extending upwardly therefrom to provide a housing 16 for the main drive shaft 17. Power is transmitted to the main drive shaft 17 through a belt connection 18, belt wheel 19, worm 20 and worm gear 21.

Upon the edges of the tub 10 is placed a cast aluminum cover 22, which is shown perhaps most clearly in Fig. 3 of the drawings. This cover is raised, as shown in Fig. 1, above the upper end of the main drive shaft 17, and as has been stated before, covers the driving mechanism for the dolly, which in the present instance is located beneath the cover and lid in an unexposed position, and with the novel result of having a dolly type of washer with a cover portion therefor that has none of the driving elements thereabove.

Attached to the upper end of the driveshaft 17 is a crank 23, with a pin 24 thereon having pivotal engagement with a pitman 25, the same having pivotal connection 26 with a raised pin 27 on a rack 28.

Before describing in detail the remaining driving mechanism, it might be stated that a second crank 29 provides the driving means for the wringer mechanism through the following portions: The wringer drive shaft 30 is keyed, as at 31, within the crank 29, which is supported in a bearing 32 positioned in the housing 33 for the wringer drive mechanism. 100

This wringer assembly is completed with the conventional gearing referred to generally as 34, the same providing the driving means for a power roll 35 of a wringer of conventional design shown at 36.

5 Returning to the description of the driving mechanism, and specifically to the rack which was designated as 28, we find that this rack is carried in a frame 37, there being provided in said frame a guideway 38, which engages a conforming groove upon the under side of the rack. A cover member 39 holds the rack in place in the frame 37. The pin 27 moves in a slot in the cover member 39.

15 Referring to Fig. 2 for perhaps the clearest showing of the frame 37, we find such frame for the rack pivoted at 40 to the cover 22. The opposite end of the frame 37 has a pivotal connection 41 with an arm 42, said 20 arm having a spring tensioned connection 43 with a crank member 44, adapted to be manually operated by a conventional handle 45 pivotally mounted in the cover 22, the movement of which is limited by the stops 46 and 25 47. The spring tensioned connection referred to generally as 43 is shown in detail in Fig. 5 of the drawings, wherein we find that a compression spring 48 is contained within slidably related cylinders 49 and 50 with the 30 result that a tensioned relationship between the crank arm and the frame is provided irrespective of the position of the frame, the same being controlled obviously by the movement of the handle 45 to either of the positions designated by the stops 46 and 47.

35 In Fig. 4 of the drawings, there is shown an enlarged detail of means for holding the frame 37 to a shelf 51 cast integrally with the aluminum cover. The means above referred to includes the screw 51a threaded into the guideway 38 and having a tensioned frictional connection through the spring 52 pressing on the washer 52a which engages the shelf 51. It is apparent from this view that lateral 40 movement of the frame may be effected through an aperture 53 therein provided for the purpose. The movement of the frame referred to above is obviously accomplished by means of the handle member, and said 45 movement of the frame which carries the rack likewise causes movement of said rack to and from the gear drive mechanism for the dolly later to be described.

50 Another tensioning means for the rack, and more particularly the frame thereof, is provided by the coil spring 54, suitably located in a projection 55 cast integrally with the cover 22.

55 Referring now to Fig. 2, for perhaps the clearest disclosure of the gear drive for the dolly, we find an intermediate gear 56 pivoted rotatably in the bearing 57 secured in the lid 58. This intermediate gear is adapted to 60 mesh with the before mentioned rack, said

gear driving the pinion 59, which in turn has mounted therein the shaft 60, the same providing the final connecting drive means for the dolly 61.

To facilitate location of the intermediate 70 gear 56 in the same plane as the rack bar, the lid is cast in such manner that a supplemental cover or lid portion 62 must necessarily be screwed thereon, in order that the upper side of the lid may be flat, as shown in 75 Fig. 1. The lid 58, as shown in Fig. 3, does not comprise the entire top of the washer, the tub being partly covered by the overlying edges of the cover 22.

The lid 58 is pivoted to the cover 22 in the 80 following manner, the same being shown in detail in Fig. 2. A bearing cap 63 is secured to the cover 22, the same having a set screw 64 threaded therein. The journal of the lid hinge bearing is shown at 65 and the lock nut 85 at 66. The actual hinge for the lid is designated at 67, the same being cast integrally therewith. Obviously, the lid 58 has two hinges, but in view of their similarity only one has been described. The other hinge is 90 located at the opposite side of the lid 58 and in alignment with the first hinge, but is not shown as it is concealed by the auxiliary cover 62 which is not broken away on that side. Located on the lid 58 adjacent the 95 hinge portion is a set screw 68, the same controlling the movement of the framing portion 37 and rack 38 towards the intermediate gear 56 by spacing the rack from the gear. In view of the fact that the lid must be raised 100 and lowered, there must be some means to prevent movement of the rack to such a position as to cause unnatural engagement of the rack with the gear in case the lid should be raised or lowered while the rack is in motion.

105 A knob or fastener 69 insures locking of the lid member 58 with the cover 22. A supplemental lid portion has been described as 62, but as a matter of fact, this portion is actually a part of the lid 58, and there is a second supplemental lid 70, which is pivoted at 71 to the lid 58 as well as an opposed point, not shown, said supplemental lid providing a covering for the rack and adjacent portion of the intermediate gear which may be raised, 110 as desired, for the purpose of viewing the driving mechanism. The pivot 71 is located at least as high as the hinge 67 and the lid 70 extends upwardly from the pivot a slight distance, as shown in Fig. 3, so as to leave a 115 space below it for the hinge. When the lid 58 is in a lowered position, this supplemental lid 70 lies in the same plane as the lid and conforms to the entire top of the washing machine, as shown in Fig. 1.

120 With respect to the operation of the washing machine and the included driving mechanism for the dolly, we find that the pitman 25, driven by the main drive shaft 17, actuates the rack 28, in a reciprocatory manner, with 125

the result that the intermediate gear 56 is rotated, as well as the pinion 59, which supports the dolly shaft 60. Means for unclutching the rack from the intermediate gear is provided in the above described frame portion 37 and crank operated handle member 47, which moves the frame and consequently the rack, into and out of engagement with said gear. A spring tensioned relationship between the rack and intermediate gear to permit a quietly running driving mechanism is provided by the use of the coil spring 54, which applies, at all times, a tension upon the frame portion in a manner to normally hold the frame and rack in engagement with the intermediate gear, and also the compression spring mounting between the frame portion 37 and the lever mechanism for moving same away from, as well as towards, the gear. This spring tensioned relationship of the rack and frame with respect to the intermediate gear prevents any possibility of breakage of the gear teeth when thrown into or out of mesh, without previously manually disengaging the rack from said gear.

A further means for insuring proper meshing of the adjacent teeth upon the rack and gear, even though there is a failure to unclutch the rack from the gear prior to the raising of the lid which carries the gear, is provided by bevelling the teeth, both on the rack, as shown at 72, and on the intermediate gear, as shown at 73.

Normally, the operation with respect to the stopping of the dolly would be effected by manual operation of the handle 47 to disengage the rack from the intermediate gear. This unclutching action would be followed by the raising of the lid 58 to permit withdrawal of the materials washed, prior to the wringing action.

It is repeated that the spring tensioned fashioning of the rack, and the bevelling of adjacent gear teeth both on the rack and the intermediate gear, prevents any possible breakage, due to the raising or lowering of the lid portion while the rack is in engagement with the intermediate gear.

It is further apparent from inspection of Fig. 1, that no parts of the driving mechanism are disposed upon the top of the washing machine, as in the well known dolly washer, and that an improved dolly machine is provided, which has a perfectly flat upper surface and an entirely enclosed driving mechanism, not only simple in construction, but providing a greatly increased degree of safety.

What I claim is:

1. A driving mechanism for a washing machine agitator comprising a gear, a rack bar for imparting alternating rotary movement to said gear, a spring tensioned movable supporting frame for the rack bar, and manually operable means adapted to move

said frame and rack into and out of engagement with said gear.

2. A driving mechanism for a washing machine agitator, comprising a gear, a rack bar for imparting motion to said gear, a pivoted frame for the rack bar, a spring normally holding said frame and rack in engagement with said gear, a lever member connected with the frame and adapted to move said frame and rack into and out of engagement with the gear, and a spring tensioned connection between said frame and lever.

3. A driving mechanism for a washing machine agitator comprising a gear, a rack bar for imparting motion to said gear, a supporting frame for the rack bar comprising a guide thereon for the rack bar, a lever member adapted to control the movement of the rack bar to and from the gear, and resilient means for pressing the rack bar into engagement with the gear.

4. In a washing machine having a tub, a cover, a pivoted lid on said cover and an agitator in said tub, driving mechanism for said agitator, comprising a reciprocating rack bar disposed beneath the cover, a pivoted frame for supporting said rack bar, a gear for actuating said agitator mounted upon the lower side of the pivoted lid, lever mechanism for controlling the movement of the frame and rack into and out of engagement with said gear, and a spring tensioned mounting for said frame.

5. In a washing machine having a tub, a cover, a pivoted lid on said cover and an agitator in said tub, driving mechanism for said agitator, comprising a reciprocating rack disposed beneath the cover, a gear mounted on the lower side of the pivoted lid for imparting motion to the agitator, and means for insuring proper meshing of the rack and gear upon movement of the pivoted lid during rack activity, including a spring tensioned support for the rack bar and a beveled fashioning of the adjacent edges of the opposed teeth members upon the rack and gear.

6. In a washing machine having a tub, a cover, a pivoted lid on said cover and an agitator in said tub, driving mechanism for said agitator, comprising a reciprocating rack bar disposed beneath the cover, a gear mounted beneath the pivoted lid and adapted to engage the reciprocating rack bar, a spring tensioned mounting for the rack bar and a lever controlling the movement of the rack into and out of engagement with said gear.

7. In a washing machine having a tub, a cover, a pivoted lid on said cover and an agitator in said tub, driving mechanism for said agitator, comprising a gear mounted on the lower side of said lid adapted to impart movement to the agitator, a reciprocat-

ing rack for actuating the gear and means permitting engagement and disengagement of the rack and gear, without breakage of the teeth while in motion, including a tensioned mounting for the rack and a beveled fashioning of adjacent teeth portions on both the rack and bar.

In testimony whereof, I have hereunto affixed my signature.

10

JOHN NELSON.
